MULTICOLOR REFILLABLE PENCIL

Willy Chatelain, Lancaster, Pa.

Application May 19, 1949, Serial No. 94,110

7 Claims. (Cl. 120—14.3)

1

This invention relates to multicolor, refillable pencils. It is an object of the invention to provide a multicolor refillable pencil which is simple and inexpensive in manufacture as well as easy and reliable in operation.

According to an important feature of the invention, the refillable pencil comprises a tubular shell within which there is concentrically arranged an assembly consisting of a member provided with longitudinal grooves on its periphery, a distributor and a chuck, a spring adapted to push the said assembly towards the back of the shell while said assembly is retained by the jaws of the chuck being in engagement with a conical bore in the front end of the shell. The grooves of the said member are intended to receive leads of different colors; the chuck is screwed to the front end of the distributor which is capable of being displaced axially but not angularly within the shell together with the remainder of the inner assembly while the grooved member is capable of angular displacements with respect to the distributor in order that each of its grooves can be brought in register with a channel of the distributor communicating with the inside of the chuck. Means are provided for marking the stoppage of the grooved member when each of the grooves is in register with the said channel of the distributor, and the grooved member is resiliently connected to the distributor in such a way that when the said grooved member is turned to bring another groove in register with the channel of the distributor, it performs also, due to the said resilient connection, a slight axial displacement away from the distributor, said displacement being due to the said means for marking the stoppage. A control knob projecting from the back end of the shell permits control of both the rotation of the grooved member and of the axial displacement of the assembly against the action of the spring which tends to push said assembly towards the back of the shell.

Further and more specific features and advantages of the invention will more clearly appear from the detailed description given below taken in connection with the accompanying drawings which form part of the specification and illustrate a preferred form of construction of the refillable pencil.

In the drawings:

Fig. 1 is an axial sectional view of a multicolor refillable pencil embodying the invention.

Fig. 2 is a cross sectional view taken substantially along the line 2—2 of Fig. 1; and

Fig. 3 is a cross sectional view taken substantially along the line 3—3 of Fig. 1.

2

The multicolor refillable pencil shown in the drawings comprises a tubular shell or casing 1 which is open at its rear extremity and the front end of which is in the shape of a truncated cone. 5 This tapered front end is formed with a conical bore 2 widening towards the outside. Within the shell 1 there is concentrically arranged an assembly consisting of a member 3, a distributor 4 and a chuck 5. 10 The member 3 is provided at its periphery with six longitudinally extending grooves 6; these grooves are arranged at 60 degrees from one another and extend from the front end of the member through a substantial length thereof. 15 The grooves 6 are intended to receive a lead or chalk 7 in each of them, each of the leads being of a different color. The distributor 4 consists of a rear portion 8 and a front portion 9. The rear portion 8 consists of a cylinder having along 20 a diametrical plane a longitudinal channel 10 the width of which is equal to that of each of the grooves 6 of the member 3. The depth of the channel 10 however increases from the end of the portion 8 which is adjacent the member 3 to 25 the other extremity adjacent the portion 9. This depth of the channel 10 varies from a depth equal to that of the grooves 6 to a depth substantially equal to the diameter of the member 3, as shown in Fig. 1. The front portion 9 of the distributor 30 has towards the back a portion having the same outer diameter as the portion 8 and fitting over the extremity of the said portion 8. The inside of this latter portion is in the shape of a funnel 11 the bottom of which communicates with an axial channel 12 provided in the front part of the 35 said portion 9. This front part is of reduced diameter and is formed at its free end with a screw tapped recess 13 in which is screwed the screw threaded extremity of the chuck 5. The latter is also formed with an inner channel 14 40 in alignment with the channel 12.

The assembly consisting of the grooved member 3, the distributor 4 and the chuck 5, is pushed towards the back of the shell 1 by means of a spring 15 resting on the one hand on the front portion 9 of the distributor, and on the other hand, on a shoulder 16 on the inner wall of the shell 1. The backward displacement of the assembly is limited by the jaws 17 of the chuck being brought into engagement with the conical bore 2 of the shell which acts on the said jaws to close them.

A longitudinal groove 18 is further provided at 120 degrees from the channel 10 in the rear portion 8 of the distributor. In this groove 18 there is engaged the point of a rivet 19 passing through

the wall of the shell 1. This arrangement permits the distributor to be axially displaced within the shell while securing the said distributor against any angular displacement.

The grooved member 3 is provided with an axial recess 19 which extends up to the rear extremity of the member 3 and whose bottom is pierced to give passage to a rod 20 having a head 21. The screw threaded end of the rod 20 is screwed in a screw tapped hole provided in the rear face of the portion 8 of the distributor. Between the bottom of the recess 19 and the head 21, there is arranged a coil spring 22 surrounding the rod 20 and adapted to maintain the member 3 against the distributor while allowing it to be turned with respect to the distributor so as to bring any desired groove 6 in register with the channel 10 of the distributor. The rear face of the distributor is formed with a small projection 23 adjacent to its periphery; this projection may consist, for instance, either of the head of a rivet forced in the portion 8 of the distributor, or of a drop of solder. The projection 23 is intended to be brought into engagement with the ends of the grooves 6. When the projection 23 is engaged in any certain groove 6, then another of the grooves is in register with the channel 10. Thus the engagement of the projection 23 with a groove marks the stoppage of the grooved member when the latter is driven in rotation. The resilient connection between the member 3 and the distributor 4 through the medium of the spring 22 permits a slight axial displacement of the member 3 with respect to the distributor when the member 3 is turned to bring another groove 6 into alignment with the channel 10, said displacement being due to the projection 23.

The inside of the recess 19 can be used as a receiver for spare leads. In the open rear extremity of the shell 1 is engaged a control knob 24 which closes the recess 19 and is intended to operate the assembly consisting of the member 3, the distributor 4 and the chuck 5. The knob 24 is provided with a slotted extremity having some resiliency and fitting the bore of the recess 19. The remainder of the knob has a diameter equal to that of the bore of the shell 1. Thus a shoulder is formed between the parts of different diameters of said knob. In alignment with said shoulder, a pin 25 is engaged radially in the knob 24. This pin comes to engage in a groove 26 provided in the rear edge of the member 3. Thus the knob 24 is adapted to cause the rotation of the member 3 by cooperation of the pin 25 with the groove 26. It operates further to produce an axial displacement of the assembly consisting of member 3, distributor 4, and chuck 5, against the action of the restoring spring 15, thus allowing the jaws of the chuck 5 to spread apart.

Behind its grooved portion, the member 3 has a hexagonal cross section, each side of which in alignment with a groove 6 and is colored according to the color of the lead which the corresponding groove is intended to receive. In front of the side that is in alignment with the groove 6 corresponding to the channel 10, there is an aperture 27 cut in the shell 1 through which the color of the side of the member 3 corresponding to that of the lead which is lodged in the groove merging into the channel 10 can be observed.

Towards the inner end of the groove 6, the member 3 is formed with a circular groove 28 in which is lodged a resilient ring 29 intended to prevent the leads from jamming in the bottom of the grooves.

30 designates a clip intended to fix the refillable pencil to the edge of a coat pocket.

The operation of the refillable pencil shown in the drawing and described above is as follows:

5 All of the leads 7 are supposed to be lodged in the grooves 6. In order to use the lead having the desired color, the knob 24 is first turned until the said color appears through the aperture 27. At this stage, the groove 6 which contains the 10 lead to be used is situated in alignment with the channel 10 of the distributor, that is to say in the position of the groove 6 shown at the upper part of Fig. 1. The refillable pencil is then inclined so as to have the chuck turned downwardly. The 15 lead 7 of the groove concerned slides through the channel 10 and penetrates into the channels 12 and 14. Simultaneously the knob 24 is pressed inwardly, thus axially displacing the assembly 3—4—5 against the action of the spring 15. The 20 jaws of the chuck 5 spread apart and the lead can enter the chuck. The length of the outwardly protruding lead portion is adjusted by hand and the knob 24 is then released. The assembly 3—4—5 is restored back by the spring 15 and the 25 jaws of the chuck are pressed against the lead by the wall of the conical bore 2 of the shell. The lead is now in position for use. If it is desired to use another lead of different color, the pencil is inclined so as to have the chuck turned 30 upwardly and simultaneously the knob 24 is pressed. The assembly 3—4—5 is displaced again against the action of the spring 15. The chuck opens and releases the lead which slides through the channel 14 and 12 and further through channel 10 back to its groove 6. The knob 24 is then released and turned at will until the desired color appears through the aperture 27. The groove which contains the lead of the corresponding color comes to a stop exactly in alignment with 40 the channel 10, due to the projection 23 engaging in a groove under the action of the spring 27 and thus distinctly marking the stoppage of the grooved member. In order to bring this new lead into proper position for use, the operation previously described is repeated. In order to take the pencil apart, it is sufficient to unscrew the chuck 17, whereby the member 3 and the distributor are released and can be removed through the rear portion of the shell 1.

50 What I claim is:

1. A multicolor refillable pencil comprising in combination a tubular shell within which is concentrically mounted an assembly consisting of a member provided with longitudinal grooves on its periphery, a distributor having a channel and a chuck having a passage in communication with said channel, a spring tending to urge said assembly towards the back of said shell, said shell having at its front part a conical bore and the 55 jaws of the chuck cooperating with the wall of said conical bore to retain said assembly, the longitudinal grooves on said member being intended to receive leads of different colors, said chuck being screwed to the front end of said distributor and the latter being displaceable axially but not angularly within said shell together with the remainder of said assembly, said grooved member being capable of angular displacements with respect to said distributor so as to enable each of its grooves to be brought into alignment with said channel provided in the distributor, means stopping said grooved member when any of the grooves is in alignment with said channel of the distributor, said grooved member being 60 resiliently connected to the distributor whereby 65 70 75

when said grooved member is turned to bring another groove in alignment with said channel of the distributor it may be axially displaced from said distributor, to clear said means stopping said grooved member, and a control knob projecting from the back of said shell manipulable for the rotation of said grooved member as well as the axial displacement of said assembly against the action of the spring which tends to urge said assembly towards the back of the shell.

2. A multicolor refillable pencil according to claim 1 characterized by the fact that the distributor consists of a rear portion and a front portion, said rear portion being constituted by a cylinder having in a diametrical plane a longitudinal channel the width of which is equal to that of each of the grooves on the grooved member, the depth of said channel increasing from the extremity of the rear portion which is adjacent the grooved member to the other extremity, and said depth varying from a depth equal to that of the grooves to a depth substantially equal to the diameter of the rear portion of the distributor, the front portion of said distributor having at its rear end a part of the same diameter as the said rear portion of the distributor and fitting over the front end of said rear portion, the inside of said rear part being in the shape of a funnel the bottom of which communicates with an axial channel provided in the front end of said front portion, said front end being of reduced diameter and having at its free end a screw tapped recess in which is screwed the threaded end of the chuck, said chuck being further provided with an inner channel in alignment with the channel of the distributor.

3. A multicolor refillable pencil according to claim 2, said distributor having a longitudinal groove arranged at 120 degrees from the channel of the rear portion thereof, said groove extending over the whole length of the rear portion of the distributor and over the part of the front portion thereof, the front portion being of the same diameter as the rear portion, a rivet passing through the wall of the shell and being engaged in said groove, whereby the distributor may be axially displaced within the shell while being prevented from being turned.

4. A multicolor refillable pencil according to claim 3, characterized by the fact that the grooved member is provided with an axial recess extending up to the rear extremity of said grooved member, and a bore below and communicating with said recess, a headed rod being screwed in the rear face of the distributor and passing through said bore into said recess, and a coil spring inserted between the bottom of said recess and the head of said rod to urge the grooved member against the distributor while allowing it to be turned with respect to said distributor so as to bring any desired groove in registry with the channel of the distributor.

5. A multicolor refillable pencil comprising in combination a tubular shell within which is concentrically mounted an assembly consisting of a member provided with longitudinal grooves on its periphery, a distributor having a channel and a chuck having a passage in communication with said channel, a spring tending to urge said assembly towards the back of said shell, said shell having at its front part a conical bore and the jaws of the chuck cooperating with the wall of said conical bore to retain said assembly, the longitudinal grooves on said member being intended to receive leads of different colors, said

chuck being screwed to the front end of said distributor and the latter being displaceable axially but not angularly within said shell together with the remainder of said assembly, said grooved member being capable of angular displacements with respect to said distributor so as to enable each of its grooves to be brought into alignment with said channel provided in the distributor, means stopping said grooved member when any of the grooves is in alignment with said channel of the distributor, said grooved member being resiliently connected to the distributor whereby when said grooved member is turned to bring another groove in alignment with said channel of the distributor it may be axially displaced from said distributor to clear said means stopping said grooved member, and a control knob projecting from the back of said shell manipulable for the rotation of said grooved member as well as the axial displacement of said assembly against the action of the spring which tends to urge said assembly towards the back of the shell, the said distributor consisting of a rear portion and a front portion, said rear portion being constituted by a cylinder having in a diametrical plane a longitudinal channel the width of which is equal to that of each of the grooves on the grooved member, the depth of said channel increasing from the extremity of the rear portion which is adjacent the grooved member to the other extremity, and said depth varying from a depth equal to that of the grooves to a depth substantially equal to the diameter of the rear portion of the distributor, the front portion of said distributor having at its rear end a part of the same diameter as the said rear portion of the distributor and fitting over the front end of said rear portion, the inside of said rear part being in the shape of a funnel the bottom of which communicates with an axial channel provided in the front end of said front portion, said front end being of reduced diameter and having at its free end a screw tapped recess in which is screwed the threaded end of the chuck, said chuck being further provided with an inner channel in alignment with the channel of the distributor, a longitudinal groove arranged at 120 degrees from the channel of the rear portion of the distributor, said groove extending over the whole length of the rear portion of the distributor and over the part of the front portion thereof, the front portion being of the same diameter as the rear portion, a rivet passing through the wall of the shell and being engaged in said groove, whereby the distributor may be axially displaced within the shell while being prevented from being turned, the grooved member being provided with an axial recess extending up to the rear extremity of said grooved member, and a bore below and communicating with said recess, a headed rod being screwed in the rear face of the distributor and passing through said bore into said recess, and a coil spring inserted between the bottom of said recess and the head of said rod to urge the grooved member against the distributor while allowing it to be turned with respect to said distributor so as to bring any desired groove in registry with the channel of the distributor, the rear face of the distributor being provided with a small projection adjacent its periphery said projection being intended to come into engagement with the ends of the grooves, one groove being stopped in alignment with the channel of the distributor each time the said projection engages a groove, the engagement of said projection in a groove marking the stoppage of the grooved member

when it is driven in rotation, the resilient connection by means of the spring lodged in the recess of the grooved member allowing the slight axial displacement of the grooved member with respect to the distributor.

6. A multicolor refillable pencil according to claim 5, characterized by the fact that said control knob closes the recess of the grooved member.

7. A multicolor refillable pencil according to claim 5, characterized by the fact that a portion 10 of the grooved member is of polygonal cross sec-

tion with just as many sides as there are grooves, each side being located in alignment with a groove and of a determined color the wall of the shell having an aperture to allow observation therethrough of the color of the side situated in front of said aperture, said color corresponding to that of the lead lodged in the groove which communicates with the channel of the distributor.
